UNITED STATES PATENT OFFICE.

ELIN NIELSEN, OF CHICAGO, ILLINOIS.

TABLE.

1,300,759.

Specification of Letters Patent. Patented Apr. 15, 1919.

Application filed June 3, 1918. Serial No. 237,908.

To all whom it may concern:

Be it known that I, ELIN NIELSEN, a subject of the King of Denmark, residing at Chicago, Cook county, State of Illinois, have 5 invented certain new and useful Improvements in Tables, of which the following, taken in connection with the drawings, is a description.

My invention has for its object the production of a table designed to be used more particularly in a work room of dress makers, tailors, milliners, and others who employ people requiring table space, and a convenient place to keep materials, thread, needles, 10 etc., being used.

A further object of my invention is to so construct such a table that it will occupy a minimum of space in the work room when not in use, and when in use will permit the 15 table tops to be drawn out from the frame of the table, to provide an individual table for each worker.

A further object of my invention is to provide a table of the class described having 20 a bin, or receptacle beneath each table top, to hold the material being used, which receptacle is open when the table top is withdrawn, giving free access to the contents of the receptacle, and when not in use, the 25 table top forms a cover for the receptacle, completely inclosing the materials, and protecting them from dust, etc.

In the accompanying drawings, I have 30 illustrated what I now consider the preferred form of my invention, although it is obvious that various changes may be made in the form and construction of the same without departing from the spirit thereof, and in these drawings:

40 Figure 1 is a top plan view of my table, the dotted lines representing the table tops partially withdrawn;

Fig. 2 is a top plan view with the table tops removed;

Fig. 3 is a side elevation;

Fig. 4 is a sectional view of the same; and

Fig. 5 is a perspective view, with the table tops in one section thereof removed, and in the other section with one table top in closed 45 position, and one partially extended.

In the drawings I have illustrated my invention comprising 4 sections, or compartments, 2 sections on each side of the table, but I wish to be understood as contemplating 50 a table with any number of sections desired to accommodate the work to be done.

Referring to these drawings, A represents uprights connected together, and braced in any suitable manner, as at a—a, to provide a supporting frame for the construction. 60

At each end of the table are transversely extending side pieces, B—B, each of which is provided with grooves, a'—a², on the inside thereof, and extending downwardly from each of which is a side member cut on 65 parallel lines to meet the center partition C.

The table may be made any length desired, divided into sections by a transversely extending strip, b, which is provided with corresponding grooves, b'—b², upon the opposite sides thereof, corresponding to the 70 grooves a'—a², arranged in the side pieces, B—B.

Slidably arranged in the grooves, a'—a², and b'—b², are the table tops, B'—B², adapted to move in opposite directions, to provide a table for each operator, and when the table top is partially withdrawn, as B², in Fig. 5, each workman will have an individual table, with a receptacle c or c', for 80 the material being used. C is a partition extending longitudinally in the center thereof, which divides the table into sections at each side, and forms a dividing wall between the receptacles, c—c', one of which is 85 arranged in operative relation with each table top.

Beneath each table top is a small receptacle, D, designed for holding thread, needles, thimbles, and small accessories used in 90 sewing rooms.

D' is an inclined wall extending from the bottom of each receptacle, c—c', to contact with the edge of the receptacle, D.

The ends of the compartments, c—c', are 95 formed by the transverse partitions, D², which are preferably located directly under the members b—B, thereby making the compartments equal in length to the table tops.

When the table is in use an operator sits at each movable section, B'—B². Each table top can be adjusted to the convenience of the individual operator, independently of the other table tops. 105

I claim:

1. In a table of the class described, the combination with uprights and bracing members of an upper surface consisting of a plurality of adjacent transverse sections, 110 said sections being separated by transversely extending grooved strips spaced at intervals

- across the top of the table, a plurality of table tops slidably movable laterally in said sections, a vertical longitudinal central partition extending the entire length of the 5 table, side members, the lower extremity of which meets said central partition at an oblique angle, transverse end partitions extending between said central and side partitions, and spaced at intervals corresponding 10 to said strips, said partitions forming receptacles beneath the table tops, said table tops adapted to overlap each other and form covers for said receptacles when the table is not in use.
- 15 2. In a table of the class described, the combination with uprights and bracing members, of an upper surface consisting of a

plurality of laterally slidable table tops forming individual work tables when extended, said tables having a plurality of 20 compartments arranged therein, the larger of said compartments being located nearest to the center of the table and having its outside partition arranged at an oblique angle to the inside partition; the smaller 25 compartment being nearest to the outside of the table, said oblique partition being extended to contact with the under side at its upper extremity, said compartments being closed by sliding the aforesaid table tops 30 into overlapped position.

In testimony whereof I have signed this specification, this 18th day of May, 1918.

ELIN NIELSEN.
